(57) **CLAIM**

I claim the ornamental design for a bottle, as shown and described.

DESCRIPTION

FIG. 1 is perspective view of a bottle showing my new design;

FIG. 2 is a front view thereof;

FIG. 3 is a rear view thereof;

FIG. 4 is a right side view thereof; the left side view being a mirror image thereof;

FIG. 5 is a bottom view thereof; and,

FIG. 6 is a top view thereof.

The broken lines in the drawing depict portions of the bottle that form no part of the claimed design.
